MEANS FOR AUTOMATICALLY STOPPING
MACHINES WHEREIN MATERIAL IS UN-
WOUND FROM A HOLDERJohn Hamilton Larmuth, Hill Crest, Upper
Colwyn Bay, North WalesApplication November 22, 1934, Serial No.
754,198. In Great Britain November 28, 1933

4 Claims. (Cl. 117—51)

This invention relates to means for automatically stopping machines wherein material such as a wire, cord, yarn, strip, tape, strand, rope or cable is unwound from a holder, such as 5 a bobbin, cheese holder or swift, some examples of such machines being stranding machines, closing machines, braiding machines, core lapping machines, and rewinding machines.

It has hitherto been proposed to provide means 10 for automatically stopping the said machines on breakage or complete exhaustion of the wire, cord or yarn, but the previously proposed means did not prevent continued running of the machine before complete exhaustion of wire, cord or yarn, 15 and the difficulties of reestablishing working conditions after exhaustion are considerably greater than just before exhaustion.

The object of my invention is to enable stoppage of the machine to take place automatically 20 at a suitable time before exhaustion of any of the materials takes place, thereby warning the operative of the necessity for replenishment before exhaustion has actually taken place and thereby avoiding the difficulties occasioned by the 25 end of the wire, cord or yarn leaving the holder before the machine stops.

Means for automatically stopping machines wherein material consisting of wire, cord, yarn, 30 strip, tape, strand, rope or cable is unwound from a holder comprises in accordance with my invention a movable feeler adapted to be restrained from outward movement by the inward pressure of one or more coils of material, and to move into a position where it will directly or indirectly set a stopping mechanism into operation, when released by unwinding of the said coil or coils.

The feeler may be in the form of a pivotal arm 40 acted on by spring means and maintained out of operative position against the action of the spring means by pressure of the said coil or coils acting through a gap or aperture in the holder.

Alternatively the feeler may be in the form of a spring forced against the holding surface or 45 into a gap or aperture therein by the coil or coils.

The feeler may be provided on a mounting adapted to be attached to or receive the holder, or on the holder itself.

In the drawings—

Figure 1 is a side view in vertical section of a 50 bobbin of a stranding machine.

Figure 2 is an end view thereof.

Figure 3 is a fragmentary side view in vertical 55 section of another bobbin of a stranding machine and illustrates another construction.

Figure 4 is a fragmentary plan view in section of a portion of a stranding machine of one kind.

Figure 5 is a fragmentary side view and

Figure 6 a fragmentary end view in section showing different details of the said machine. 5

Figure 7 is a plan view in section of a portion of a stranding machine of another kind, and

Figure 8 is a fragmentary end view in sections showing a detail thereof.

Figure 9 is a fragmentary plan view of a portion 10 of a stranding machine of still another kind, and

Figure 10 is a diagrammatic end view of a portion 15 of the last named machine.

Figure 11 is a fragmentary view in longitudinal section of a base tube and paper tube of a brading 20 machine.

Figure 12 is a fragmentary elevation thereof regarded from another angle.

Figure 13 is a fragmentary plan view of a part 25 of a braiding machine.

Figure 14 is a fragmentary view in vertical section taken on line 14—14 of Figure 13.

Figure 15 is a fragmentary elevation of a paper 30 tube of a braiding machine and illustrates a modification.

Referring to the drawings, in the construction of bobbin shown in Figures 1 and 2, the bobbin 1 has an axial hole 2 provided in one end and breaking through the holding surface 3 and 4 to form an aperture in the said surface. The hole 2 30 is engaged by an axially arranged plug 5 having a flange 6 which is situated outside the hole 2 and is suitably secured for example by screws 9, to the end of the bobbin 1. The plug 5 has an extension 7 situated in the interior of the bobbin. 35

A slot 8 extending from end to end of the plug 5 and through the flange 6 and extension 7, and situated radially relative to the bobbin 1 is provided and accommodates an arm 10 which has one end pivotally mounted at 83 in the slot 8. 40 The arm 10 is free to move in the slot 8 and extends outside the end of the bobbin 1. A radial cavity is provided in the flange 6 to accommodate a compression spring 11 which acts to turn the arm 10 in a radially outward direction. 45

The arm 10 has a feeling surface 12 which engages the aperture 4 in the holding surface 3 and lies flush with the said surface when the arm 10 is in the inoperative position (shown in full lines), and the spring 11 acts to force the feeling 50 surface 12 above the holding surface 3 and the projecting end of the arm from one position into another (indicated by dot-and-dash lines.)

In operation, the winding of the material, for example wire, on to the holding surface 3 of the 55

bobbin 1 is commenced from the opposite end to that hereinbefore referred to and proceeds towards the last named end until a coil or coils 13 extend over the slot in the bobbin and depress the 5 arm 10 against the action of the spring 11.

In the unwinding of the bobbin 1 a time arrives when the said coil or coils 13 are unwound from the bobbin 1 and release the arm 10 which is thereupon swung outwards by the spring 11, 10 whereby the projecting end of the arm 10 is caused to occupy a new position, see dot-and-dash lines, and actuate mechanism for automatically stopping the machine before the last portion of the material has been unwound from the bobbin.

15 Figures 4 to 6 show one form of mechanism for actuation by the said arm, applied by way of example to a stranding machine in which the bobbin 1 is carried by a cradle 14 mounted by means of trunnions 15 and brackets 16 and 21 20 inside the rotary tube 17 or frame of the machine. The mechanism comprises a slidable rod 18 connected to a slide 19 mounted slidably on the cradle and acted on by a compression spring 20 which operates to push the rod 18 towards 25 the bracket 21.

The slide has a keyhole slot 22 the enlarged part of which is normally engaged by a head 23 of a pin 24 to lock the slide 19 and rod 18 against the action of the spring 20. The pin 24 is retained in the locking position by a compression spring 25, and in this position its conical end 26 is struck by the arm when the arm is in the position shown in dash-and-dot lines in Figure 1 and the bobbin 1 is rotating. Impingement of 30 the arm against the end 26 actuates the pin 24 against the action of the spring 25 and thereby forces the head 23 out of the keyhole slot 22. On the slide 19 and rod 18 being thus released, the action of the spring 20 displaces them to 35 40 wards the bracket 21.

The bracket 21 is provided with a slide 27 loaded by a compression spring 28 and having a rod 29. The slide 27 is locked by the head 30 of a pin 31 against actuation by the spring 28, the 45 said head being held in engagement with the enlarged part of a keyhole slot 32 provided in the slide 27. The pin 31 is retained in the locking position by a compression spring 33 until the rod 18 is displaced towards the bracket 21, where- 50 upon the rotation of the pin 31 with the bracket 21 and tube 17 or frame causes its conical end 34 to impinge against the rounded head 35 of the rod 18 and the pin 31 to be thereby actuated against the action of the spring 33 to release the 55 slide 27. The spring 28 thereupon actuates the slide 27 and rod 29 in an outward direction. The rod then impinges against and actuates the turn- 60 able control arm 36 of an electric switch 37 which controls the drive of the machine. The rod 29 may alternatively control an automatic belt shifting motion or other means of bringing the machine to a standstill.

In Figures 7 and 8 the bobbin 1 is shown in use in a stranding machine wherein the bobbin 1 is mounted on a mandrel 38 mounted co-axially with the rotary tube 39 or frame in brackets 40 and 41 provided on the tube 39 or frame. A spring loaded slide 42 and rod 43 are slidably mounted on the bracket 41 and locked in the 65 withdrawn position by means of a head 44 provided on a pin 45 and engaging the enlarged part of a keyhole slot 46 in the slide 42. The pin 45 is held in the locking position by a compression spring 48 until its conical head 47 is struck by 70 the arm 10 on the rotating bobbin 1 after the 75

latter has been allowed to assume its operative position by removal of the coil or coils which control it. The rod when in the outwardly projected position serves to actuate locally stationary means which when actuated bring the machine 5 to a standstill.

Figures 9 and 10 show the use of bobbins 1 in a stranding machine in which the bobbins 1 are mounted in cradles 49 to revolve about a common centre 48. Each cradle 49 is provided with rod, slide and pin means 50, 51 and 52 similar to the rod, slide and pin means 18, 19 and 25 of Figures 4 and 5, but with the rounded head 25 omitted. Electric switches having arms 53 or other drive controlling means or trip motions 15 are fixed in position where they will be operated to stop the machine when any of the rods 50 move into operative position.

If it is desired that the arm on the bobbin shall come into operation when a less number 20 of coils than that shown remains on the bobbin, the arrangement shown in Figure 3 may be employed instead of that shown in Figures 1 and 2. In Figure 3, an arm 54 extends across the width of the bobbin and is pivoted at 55, its end being 25 acted on by a compression spring 56 which operates to turn the arm into the position shown in dot-and-dash lines. The arm 54 has a feeler surface 57 on a lug 58 which is accommodated by a slot 59 in the holding surface 60 of the 30 bobbin. The arm 54 is released when only half a layer of coils remains on the bobbin. By positioning the lug 58 and slot 59 at the requisite point along the width of the surface 60, the arm 54 can be released when the remaining coils on 35 the surface 60 have fallen to any desired number.

In another construction, as applied by way of example to a braiding machine, each cheese is mounted on a holding tube 61 provided with an axial slot 62 in the end and the tube 61 is placed 40 on a base tube 63 having an axially directed rib 64 which engages the slot 62. The rib 64 has a slot 65 in which one end of an arm 66 is pivoted at 67 to swing laterally of the tube 63. A spring 68 provided in a hole 70 in the tube 63 acts 45 on the arm 66 to drive it outwards. The arm 66 has a feeling surface 71 which is acted on by one or more coils 72 near the end of the material forming the cheese, where the coils extend across the slot 62, whereby the arm 66 is held in inopera- 50 tive position against the action of the spring 68.

This construction operates in a similar manner to the previously described construction, the arm 66 when released by the unwinding of the said coil or coils 72 being forced by the spring 66 55 into a new position where it is capable of actuating a trip motion direct or through a suitable mechanism.

Figures 13 and 14 illustrates two of the said tube 61 and base tubes 63 employed in horizontal 60 and vertical positions respectively on a braiding machine comprising a shuttle 73 rotating in a circular path inside an annular table 74 which also rotates in the reverse direction. The mechanism shown for operating a locally stationary 65 trip motion when the arm 66 of the horizontal base tube 63 is in its projected position comprises a spindle 75 which is turnably mounted on the table 74 and has a striking arm 76 above the table 74 and a motion transferring arm 77 beneath the table 74. The arm 77 is connected to a rod 78 which is slidably mounted beneath the table. The shuttle 73 is furnished with a pin, slide and rod arrangement similar to those hereinbefore described, the rod 80 of the said 70 75

arrangement when projected striking the arm 76 and thereby causing the rod 78 to be projected to operate the locally stationary trip motion.

The mechanism shown for operating the locally stationary trip motion when the arm 66 of the vertical base tube 63, Figures 13 and 14, is in the projected position comprises a bracket 79 supported by the table 74 and carrying a pin, slide and rod arrangement similar to those hereinbefore described, the rod 80 of the said arrangement serving when projected to operate the locally stationary trip motion.

Instead of providing the arm 66 on the base tube 63, it may be provided on the holding tube 61.

15 Instead of an arm 66 on a slotted holding tube 61, a spring 81, Figure 15 may be employed on a non-slotted holding tube 82 to be resiliently pressed by the coil or coils against the holding surface of the tube 82 into an inoperative position and flex into the shown operative position when relieved of pressure by the unwinding of the said coil or coils.

I claim—

1. In a machine comprising a rotating holder 25 from which material is uncoiled, a differently rotating part on which the holder is mounted, and a locally stationary trip motion, an automatic stopping means comprising in combination a spring-loaded feeler provided on the rotating holder and moving into an active position when released by the uncoiling of the material, a spring loaded catch pin which is slidably mounted on the said differently rotating part and is tripped by the said feeler, a spring loaded slide rod 30 which is also mounted on the differently rotating part and is held by the said catch pin until the catch pin is tripped but is projected when the said pin is tripped for impingement against the locally stationary trip motion.
2. In a machine possessing a rotating part, a cradle floating in the rotating part, and a bobbin rotatably mounted in the cradle at right angles to the axis of rotation of the rotating part, the combination of a machine stopping trip motion 35 located adjacent the rotating part, a spring loaded rod rotating with the rotating part for actuation of the stopping device, a spring loaded catch rotating with the rotating part for releasably holding the said rod in an inoperative position, a spring loaded rod provided on the

cradle for release by the spring loaded catch, a spring loaded catch provided on the cradle for releasably holding the second named rod in an inoperative position, and a feeler provided on the bobbin and controlled by material coiled thereon 5 for tripping the last named spring loaded catch when nearly all the material has been uncoiled from the bobbin.

3. In a machine possessing a rotating part, a member free to rotate independently of the rotating part and a bobbin rotatably mounted in the said member at right angles to the axis of rotation of the rotary part, the combination of a trip motion located adjacent the rotating part, a rod slidably mounted on the rotating part and 10 operatively impinging in one position against the trip motion, means on the rotating part for producing movement of the rod into the said position, a spring-loaded rod slidably mounted on the said member and operatively impinging in 15 one position against the said means, a spring catch provided on the said member for holding the second named rod out of the said position, and feeler means provided on the bobbin and controlled by material coiled on the bobbin for 20 releasing the spring catch by impingement thereagainst when the said material is nearly exhausted.

4. The means for automatically stopping machines wherein material is carried in coils on a 30 rotary holder which is mounted on a cradle floating in bearing brackets provided on a rotary member, comprising oscillatable means provided on and rotating with the bobbin in combination with a spring-loaded catch on the cradle for actuation by lateral impingement of the oscillatable means thereagainst, a slidable spring loaded rod 35 on the cradle for release by the said actuation of the spring-loaded catch, a spring loaded catch on one of the said bearing brackets for release 40 by lateral impingement of the spring-loaded rod thereagainst, a slidable spring-loaded rod on the said bracket for release by the second named spring-loaded catch, a stopping trip motion located adjacent the said rotary member, and a 45 trip member on the said trip motion for actuation by lateral impingement of the second named spring rod thereagainst.

JOHN HAMILTON LARMUTH. 50
